(57) **CLAIM**

The ornamental design for a carrier pouch, as shown and described.

DESCRIPTION

FIG. 1 is a perspective view of a carrier pouch showing my new design;

FIG. 2 is an exploded view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings illustrate portions of the carrier pouch that form no part of the claimed design. The patches of cross-hatching represent a texture that continues throughout the surfaces.
